(57) **CLAIM**

We claim the ornamental design for a handle for oven door, as shown and described.

DESCRIPTION

FIG. 1 is a front perspective view of a handle for oven door showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

(Continued)

FIG. 8 is a rear perspective view thereof; and,
FIG. 9 is a cross-sectional view taken through line 9-9 of
FIG. 2.

The broken lines in the figures depict portions of the handle
for oven door which form no part of the claimed design.

1 Claim, 9 Drawing Sheets
